LINE CASTING MACHINE

Application filed June 30, 1931. Serial No. 547,994.

The present invention relates to improvements in line casting machines and more especially to those of the general class shown and described in U. S. Letters Patent No. 436,532 granted September 16, 1890 to O. Mergenthaler, wherein matrices bearing type forming characters are assembled in a line and the line is lowered by a so-called first elevator to a position in front of a mold and the mold is then brought forward to form a metal-tight lock-up with the matrix line, after which the molten type metal is injected into the mold to cast a type bar or slug against the character bearing face of the matrix line, following which the mold breaks away and recedes from the matrix line and the elevator then operates to remove the matrix line for distribution of the matrices therefrom, and the invention relates more particularly to machines of this class as now generally constructed which are adapted to use matrices provided with type forming characters at upper and lower levels thereon and which embody means for stopping the descent of the elevator at either a lower or an upper alignment position to bring the upper or lower matrix characters to the casting level relatively to the mold.

In the operation of machines of this class as heretofore constructed, in casting from the matrix line while the latter is positioned at the upper casting level, the elevator supporting the matrix line usually sags or drops slightly when the mold breaks away from the matrix line, and this has caused damage to and mutilation of the type characters cast on the type bar or slug, and the object of the present invention is to provide means for supporting the elevator and the matrix line therein at such time to prevent such sagging or dropping and thereby avoid such damage or mutilation of the type characters.

In the accompanying drawings:

Fig. 1 is an end elevation of a portion of a line casting machine embodying the present invention;

Fig. 2 is a vertical section taken through the upper portion of the first elevator and through the mold and cooperative parts of the machine;

Fig. 3 is a detail view on an enlarged scale, partly in section, taken vertically and longitudinally through the head of the first elevator and the vise cap; and

Fig. 4 is an enlarged vertical section through the mold and a portion of the first elevator which alines the matrix line therewith.

The invention is shown applied to a line casting machine of the class hereinbefore referred to, the machine comprising, as usual, a main frame 1 on which the operative parts of the machine are mounted, 2 representing the so-called first elevator which is guided to reciprocate vertically in suitable guides on the usual vise frame 3, the head 4 of the elevator having jaws 5 as usual which form a channel to receive a line of matrices M and spacebands S which are previously composed in the assembling mechanism of the machine and transferred in the usual and well known way to the first elevator while the latter is positioned at a suitable receiving level. The first elevator, after receiving the matrix line, is lowered to present the matrix line in front of a mold 6 which is formed as usual with a slot 7 in which a type bar or slug is to be cast, the body of the mold being formed on its face with upper and lower grooves 8 and 9 to form upper and lower rails against which the lower rear lugs or ears on the matrices are adapted to aline, and the mold is carried by a mold wheel or disk 10 which is mounted as usual on a slide so that it is movable forwardly and rearwardly to bring it into engagement with the rear face of the matrix line preparatory to a cast and to recede therefrom, following the cast, to permit rising of the first elevator and the matrix line, following which the matrices and spacebands composing the line are distributed in the usual well known way.

While the mold is in engagement with the matrix line and the slot or cavity 7 therein is alined with the type forming characters in the matrices, molten metal is injected into the mold to cast the type bar or slug, the injection of the molten metal being effected usually from a metal pot, the throat 11 of which is provided with a mouthpiece 12.

which is adapted to engage and form a metal-tight joint with the rear face of the mold, this mouthpiece having orifices through which the molten metal is injected into the mold. The mold wheel carrying the mold may be advanced and retracted by the means usually employed in machines of this class for this purpose, and the metal pot may be advanced to form a lock-up between its mouthpiece and the mold and between the mold and the matrix line and retracted by the means usually employed in machines of this class for this purpose.

In line casting machines of this class as now commonly constructed, matrices having type forming characters punched or otherwise formed in intaglio at different levels therein are used, and the matrix lines are presented to the mold at different levels according to whether the type bar or slug is to be cast from the lower or upper matrix characters. The first elevator is usually lowered and raised to carry the matrix line therein to and from a position in front of the mold by a lever 13 which is pivoted to the main frame of the machine at 14 and is connected by a longitudinally compressible link 15 to the elevator, and the lever 13 is connected to an arm 16 which carries a roller 17 which rides on the periphery of a cam 18 under the weight of the elevator, this cam being mounted on the main cam shaft 19 of the machine which is set into operation at an appropriate time in the cycle of operations of the machine, as is well known in the art. The cam 18 has a portion 20 with which the roller 17 cooperates while the elevator is in its lowermost position, a portion 21 with which said roller cooperates while the elevator is lifted slightly from its lowermost position to bring the lugs or ears on the matrices into alinement beneath one of the alining rails on the mold, a slightly recessed portion 22 which the roller 17 enters and allows the lifting force exerted on the elevator to be relaxed to relieve the upward pressure of the matrix ears on the alining rail of the mold, and the portions 23 and 24 on the cam cooperate with the roller 17 to lift the elevator successively to its uppermost or matrix line removing position and to its intermediate or matrix line receiving position.

The vise cap 25 on the vise frame 3 is provided with an alining bar 26 which is slidable horizontally in a groove in the top of the vise cap and the alining bar is provided with one or more pins 27 which project upwardly above its surface, the alining bar being shiftable to bring it or one of the pins thereon into position beneath a banking screw 28 mounted in the head 4 of the elevator, the screw 28 engaging directly on the upper side of the bar 26 when the elevator descends to its lowermost level as when the upper character punchings in

the matrices are to be alined with the mold, and the screw 28 engaging on the top of one of the pins 27 to arrest the descent of the elevator at a relatively higher alinement level, as when the lower character punchings, or character punchings at a third or auxiliary level as in three-letter matrices or matrices with very large one-letter display characters are to be alined with the mold.

In the normal operation of a machine of this class and when casting from matrix lines presented to the mold in the normal or lowermost position, which brings the upper matrix characters into position to be alined with the mold slot, the first elevator 2 moves downwardly under control of the cam 18 until the banking screw 28 rests on the top of the slidable alining bar 26, the portion 20 of the cam 18 then engaging the roller 17. Immediately thereafter, the mold wheel 10 carrying the mold 6 in which a slug is to be cast, advances against the line of matrices in the first elevator, and the metal pot advances until its mouthpiece 12 seats firmly against and forms a metal-tight seal with the back of the mold. In order to permit the lower lugs or ears on the matrices to freely enter the alining grooves in the mold, the machine is so constructed as to allow a slight clearance between the upper edges of the matrix ears and the upper face of the mold alining groove 9 when the first elevator is seated on the alining bar 26. After the matrix ears have fully entered the alining groove, the first elevator rises from the alining bar 26 a distance equal to the clearance provided between the matrix ears and the mold alining groove, as described above, in order to press the lower lugs or ears on the matrices firmly upwardly against the upper face of the mold alining groove in order to insure perfect alinement of the matrices, and this slight rise of the elevator to aline the matrices against the mold is effected by the continued rotation of the cam 18 in the direction indicated by the arrow in Fig. 1, which brings the slightly raised portion 21 of the cam into engagement with the roller 17, the movement thus imparted to the roller 17 by the raised portion 21 on the cam being transmitted to the first elevator 2 through the arm 16 and lever 13 and through the yielding or compressible link 15 which connects the lever 13 to the first elevator.

Immediately after the slug is cast in the mold, the cam 18 will have reached a position where the roller 17 is in contact therewith at the recessed portion 22, and the gradual recession or dropping away of this portion of the cam, which is followed by the roller 17, causes the upward drive or lifting force exerted on the elevator to become relaxed, in consequence of which the upper

edges of the matrix ears move slightly downwardly or away from the upper face of the lower mold alining groove during the breaking away or retraction of the mold from the matrix line, so that the matrix ears will not be caused to drag against the upper wall of the mold groove during disengagement therefrom and thereby cause objectionable wear on the parts, although the yielding link 15 will be sufficiently compressed during casting from lines positioned at the normal or lower alinement level to support the weight of the assembling elevator and thus prevent undue dropping or sagging of the matrix line relatively to the mold.

In casting slugs from matrix lines while the latter are in an upper or high alinement position, as when the lower matrix characters are alined with the mold slot, the actions are generally the same as just described except that the first elevator is stopped in its descent by a high alinement pin 27 on the alining bar 26, and is lifted from this pin to aline the matrix ears against the mold preceding the cast. This higher position occupied by the first elevator, however, causes the roller 17 to leave contact with the cam 18 when the recessed or receding portion 22 of the cam comes opposite to the roller, because the first elevator is arrested in its descent by the high alinement pin 27, and the roller 17, lever 13 and link 15 are then unable to support the first elevator in such high alinement position. Consequently, when the mold reacts or breaks away from the matrix line following the cast at the upper alinement position of the first elevator, the latter has heretofore been permitted to drop onto the high alinement pin, and the weight of the first elevator which was brought to bear on the type character face of the slug and which still projected into the character punchings of the matrices, which latter are held immovably in the jaws of the first elevator, has subjected the type character face to a shearing action which, due to the softness of the type metal composing the slug, damaged or mutilated the type characters, the compression of the yielding link 15 being insufficient to avoid dropping of the first elevator when the mold breaks away, owing to the higher position then occupied by the first elevator.

The present invention provides means for sustaining the weight of the first elevator, during casting from the matrix line while in the high alinement position, when the roller 17 is over the portion 22 of the cam 18 and hence the elevator is unsupported by the cam 18, against dropping during the break-away of the mold or withdrawal of the characters on the slug from the character punchings in the matrices from which the slug was cast, thereby avoiding damage or mutilation of the cast type characters, especially those having

descending stems, through the shearing action described above.

In the embodiment of the invention herein shown, such auxiliary supporting means for the first elevator comprises a stepped block 29 or equivalent solid abutment which is movable into a position to prevent dropping of the first elevator into contact with the high alinement pin 27 during break-away of the mold from the matrix line while casting from the matrix line when the latter is in high alinement position and the roller 17 is out of contact with the cam 18, the block 29 shown being slidable preferably in a groove 30 formed in the upper side of the vise cap 25 and having steps 29a on its upper surface one or another of which is adapted to engage beneath an edge of the first elevator head as at 31, these steps being graduated in height according to the different alinement levels which the first elevator may occupy to hold it substantially in its lifted matrix alining position at the different levels during the break-away of the mold from the matrix line. The block is movable into a position between the vise cap and the first elevator head to bring one of its upper steps into engagement with the latter while the banking screw 28 is lifted above the corresponding high alinement pin 27, as when the lugs or ears on the matrices are lifted into alinement against the upper edge of the upper alining groove 8 on the mold by the engagement of the raised portion 21 of the cam with the roller 17; the block then supporting the first elevator substantially in its lifted matrix alining position or against dropping back onto the pin 27 while the mold breaks away and recedes from the matrix line, the block being retracted from beneath the elevator head in the intervals between the casting operations. As shown, the slidable block is operatively connected to an end of a rod 32 which is guided to slide longitudinally in a bearing 33 formed on a bracket 34 which latter is fixed to the vise cap, the rod 32 having a collar 35 fixed thereon and having a spring 36 which bears at its ends against the bearing 33 and collar 35 and acts yieldingly to move the block 29 in a direction to assume a position beneath the first elevator head. The outer end of the rod 32 is pivotally connected to one arm of a bell-crank lever 37 which is pivoted at 38 to an arm 39, the latter being fixed to the bracket 34, and the other arm of the bellcrank lever is connected to an operating rod 40, which as shown is reciprocatory vertically.

The rod 40 may be actuated to set the block 29 in and out of operative position beneath the head of the first elevator by any suitably timed moving part of the machine, thus effecting automatic operation of the first elevator supporting block. It has been found for example that the roller 41 on the usual justifying lever 42, which is pivoted on the

main frame of the machine at 43, contacts with its cam 44 in the position shown in Fig. 1 at the moment the break-away of the mold from the matrix line takes place, and the justifying lever 42 is shown in the present instance as utilized to effect the operation of the block controlling rod 40, the forked end 45 of this justifying lever being provided with a pin 46 and the lower end of the rod 40 being provided with a vertically elongated slot 47 in which the pin 46 operates under the control of the cam 44 and the spring 48 which acts to lift the justifying lever and to maintain its roller 41 in contact with said cam.

15 In operation, the lever 42, through contact of its roller 41 with its controlling cam 44, is held down except when the roller 41 is in the depressions in the contour of said cam, so that the pin 46 will be at the bottom of the slot 47 in the rod 40 and the latter will be held down, in consequence of which the block 29 will be held in retracted position against the action of the spring 36, the block being then clear of the head of the first elevator.

20 25 However, as soon as the roller 41 enters the depression 49 in the cam 44, which occurs immediately prior to the break-away of the mold from the matrix line following a cast, the lever 42 begins to rise under the action of the spring 48, thereby lifting the pin 46 from the lower end of the slot 47 and allowing the spring 36 to expand and shift the rod 32 toward the left in Fig. 3, thereby moving the block 29 into position beneath the edge of the head of the first elevator, as shown in Fig. 3. At this time the first elevator will have been lifted to aline the matrix lugs or ears against the upper edge of the upper alining groove 8 in the mold, the banking screw 28 being lifted above the high alinement pin 27, and moving of the block beneath the head of the first elevator will cause the block to support the first elevator against dropping more than a very small amount such as .001" or .002" which will be sufficient to relax the upward pressure of the matrix lugs against the mold while the mold breaks away from the matrix line, notwithstanding that the roller 17 at this time is opposite to the recess 22 and is out of contact with the cam 18, such slight dropping of the first elevator during the break-away being permitted without damaging the type characters due to the usual tapered form of such characters and of the matrix character punchings in which they are cast.

25 30 35 40 45 50 55 60 65 Further rotation of the cam 44 will carry the depression 49 therein past the roller 41 as shown in Fig. 1 and cause the pin 46 in the lever 42 to engage the lower end of the slot 47 in the rod or link 40, thereby pulling the latter downwardly and withdrawing the block 29 from the path of the head of the first elevator. At this period in the normal cycle of operations of the machine, however,

the slug has been cast and the mold has been retracted in the usual manner so that the drop of the first elevator back to the position where the banking screw 28 contacts with the alining pin 27 will occur after the type character bearing edge of the slug has been completely withdrawn from the character punchings in the matrices, and hence no damage can occur to the type bearing edge of the slug, the break-away of the mold from the matrix line having taken place while the first elevator is held up off its alining pin 27 by the block 29.

70 75 80 85 90 95 100 105 110 115 120 125 For casting slugs from the upper characters on the matrices, the alining bar 26 is moved toward the right in Fig. 3 by the operator so that the first elevator can descend until its banking screw 28 rests directly on the top of this bar, and while the block 29 will advance and retract as above described during casting from the matrix line while the first elevator is at the lower or normal alinement level, only the lowermost step on the block will enter beneath the head of the first elevator, due to the lower position then occupied by the elevator head, but since this lowermost step of the block is of a height which will support the first elevator substantially in its lifted matrix alining position at the lower alinement level and will permit the roller 17 to enter the depression 22 in the cam 18, and the first elevator is always supported by the roller 17 which remains in contact with the cam 18, due to the degree of compression of the yielding link 15, while the first elevator is at the lower alinement level, the block 29 will then allow the first elevator to drop slightly from its lifted matrix alining position to relax the pressure on the matrix lugs when the depression 22 in the cam reaches the roller 17 during the mold break-away, as usual while casting at the lower alinement level, but will be a safeguard against undue dropping of the elevator in case of wear of the cam or misadjustment of the link spring.

125 It will be understood that while the degree of compression of the usual spring in the link 15 is insufficient to support the elevator in its lifted matrix alining position at the upper alinement level when the rollers 17 is opposite to the recession 22 in the cam, at which time the break-away of the mold and the slug cast therein from the matrix line takes place, the raised portion 21 of the cam is sufficiently high to compress the link to a degree that will lift the elevator and the matrix line into alinement against the mold to take up the usual slight clearance of about .010" between the lower rear matrix ears and the alinement groove in the face of the mold while casts are being made at the upper alinement level, so that proper lifting of the matrix line into alinement with the mold is insured, whether casts are being made at the upper or lower alinement level, the increased lift-

ing force exerted on the roller 17 by the raised portion 21 while casts are being made at the lower alinement level being taken up by the yielding link 15, and that when the low portion 5 20 of the cam is opposite to the roller 17 while casting at the lower alinement level the elevator may descend fully to its lowermost position since the yielding link is then compressed sufficiently under the weight of 10 the elevator.

I claim as my invention:—

1. In a line casting machine comprising a slug casting mold, an elevator for presenting a line of matrices thereto, means for advancing the mold toward the matrix line to form a lock-up therewith, and means for lifting the elevator to aline the matrices against the mold, means independent of the elevator lifting means for holding the elevator substantially in its lifted matrix alining position.

2. In a line casting machine comprising a slug casting mold, an elevator for presenting a line of matrices thereto, means for advancing the mold toward the matrix line to form a lock-up therewith and for retracting the mold after a cast has been made, and means for lifting the elevator prior to the cast to aline the matrices against the mold, means operative by a part of the machine independent of the elevator lifting means for supporting the elevator in substantially its lifted matrix alining position during retraction of the mold.

3. In a line casting machine comprising a slug casting mold, an elevator for presenting a line of matrices to the mold at upper and lower levels, means for advancing the mold toward the matrix line to form a lock-up therewith, and means for exerting a lifting force on the elevator to lift it from either of said levels to aline the matrices against the mold and for subsequently relaxing such lifting force, means operative while said lifting force is relaxed, to hold the elevator substantially in its lifted matrix alining position at the upper level.

4. In a line casting machine comprising a slug casting mold, an elevator for presenting a line of matrices to the mold at upper and lower levels, means for advancing the mold toward the matrix line to form a lock-up therewith and for retracting the mold after a cast has been made, and means for exerting a yielding lifting force on the elevator to lift it from either of said levels to aline the matrices against the mold prior to the lock-up and for relaxing such lifting force prior to the retraction of the mold, means operative by a part of the machine independent of the elevator lifting means to support the elevator substantially in its lifted matrix alining position at the upper level and inoperative after retraction of the mold.

5. In a line casting machine comprising a slug casting mold, an elevator for presenting

a line of matrices thereto, means for advancing the mold toward the matrix line to form a lock-up therewith, means for lifting the elevator to aline the matrices against the mold and means for justifying the matrix line presented to the mold, means operative by such justifying means for holding the elevator substantially in its lifted matrix alining position.

6. In a line casting machine comprising a slug casting mold, an elevator for presenting a line of matrices thereto, means for advancing the mold toward the matrix line to form a lock-up therewith, and means for lifting the elevator to aline the matrices against the mold, a support movable into direct supporting engagement with the elevator to hold it substantially in its lifted matrix alining position.

7. In a line casting machine comprising a slug casting mold, an elevator for presenting a line of matrices thereto, means for advancing the mold toward the matrix line to form a lock-up therewith, and means for lifting the elevator to aline the matrices against the mold, a block movable into and out of supporting relation with respect to the elevator to hold it substantially in its lifted matrix alining position.

In testimony whereof I have hereunto set my hand.

JOHN W. BITTNER.
